UNITED STATES PATENT OFFICE.

OLAF E. OLESON, OF CHICAGO, ILLINOIS.

VALVE.

No. 905,218.

Specification of Letters Patent.

Patented Dec. 1, 1908.

Application filed June 21, 1907. Serial No. 380,016.

To all whom it may concern:

Be it known that I, OLAF E. OLESON, a citizen of the United States, residing at Chicago, in the county of Cook and State 5 of Illinois, have invented a certain new and useful Improvement in Valves, of which the following is a full, clear, concise, and exact description, reference being had to the accompanying drawings, forming a part of 10 this specification.

My invention relates to valves, particularly steam valves, its object being to provide a valve in which the effects of wire drawing are obviated.

15 With my improved construction the valve seat is automatically cleaned by the steam flow before the valve seats, and cutting or abrasion of the valve seat is prevented.

In the accompanying drawing this construction is set out in detail, the figure being 20 an elevation view of a valve structure, part thereof being a longitudinal, diametrical section.

The casing 1 of the valve has the coupling 25 flanges 2 and 3 and the inlet and outlet passageways 4 and 5 respectively. The inner end of the passageway 5 is threaded at 6 and provides the annular shoulder 7 against which engages the horizontal flange 8 of the 30 annular valve seat member 9, which threads into the upper end of the outlet. The outer end of the flange 8 is rounded on top to form the annular bead or ridge 10 which forms a valve seat. The member 9 has also the vertical flange 11 which extends above the plane 35 of the seat 10 and whose top face is preferably in a plane with the lower edge 12 of the inlet passageway 4. The seat member 9 is readily secured in the outlet passageway by 40 means of a suitable tool engaging the lugs or extensions 13.

On the valve casing is mounted the bonnet 14 comprising the cap part 15 which is suitably secured to the top of the casing, and the 45 yoke members 16 joining the hub at 17 at which is shown a bushing 18, whose inner bore is threaded for receiving the threaded valve stem 19. To the upper end of the stem is secured the hand wheel 20. The stem 50 extends into the valve chamber and passes through the guide opening 21 and through the cap 22 for the stuffing box 23. The lower end of the stem has the head 24 and collar 25 forming the groove 26. The head 24 engages in the groove 27 of the valve 28, while the locking flanges 27' at the edge of this

groove engage in the groove 26, vertical movement of the stem then causing vertical movement of the valve 28. This valve 28 has the annular flange 29, extending downwardly to engage with a steam tight fit in the valve seat member 9. The valve has the outer flange 30 for engaging the valve seat 10 when the valve is closed, and this flange at its outer edge has the protecting ridge or bead 31. Between the inner flange 29 and the outer flange 30 is the groove 32. The face of the inner flange is preferably below the face of the outer flange, and when the valve is closed, the face of the inner flange is also below the plane of the valve seat. The depth of the slot 32 is also such that when the valve is closed, there will be a chamber 33 formed by the walls of this slot, and the upper face of the seat member. 70 There will also be an annular chamber or pocket 34 when the valve is closed, formed between the flanges 11 and 8, the valve seat 10 and the outer flange 30. The inner diameter of the outer valve flange is also 75 slightly greater than the outer diameter of the vertical flange of the seat member.

In the drawing the valve is shown closed. Upon turning of the hand wheel, the valve stem and valve are raised. The flange 30 is carried from the seat 10, but there will be no flow through the valve until the lower end of the flange 29 leaves the upper end of the flange 11. The lower outer edge 35 of the flange 29 is beveled, as shown, so that the passageway through the valve will be rapidly opened wide, the steam flowing into the inlet passageway 4 over the valve seat and into and through the outlet passageway 5. During the passage of steam through 90 the valve, grit, dirt or other foreign substances are apt to lodge on the valve seat or on the upper surface of the flange 11, but when the valve is opened, the flow of steam across the face of the flange 11 creates more 100 or less suction over the valve seat, and the steam will carry with it and from the valve seat any dirt or other foreign substance which might otherwise lodge. In fact, if there are any such foreign particles in the 105 incoming steam, they will not reach the valve seat, but will all pass out through the valve. When the valve is closed and the lower edge of the flange 29 approaches the flange 11 of the seat member, the suction 110 effect over the valve seat is reduced and particles might lodge on the valve seat and

injure the valve seat when the valve is finally brought into engagement therewith, but for an instant when the flange 29 enters the seat member there will be a slight 5 wire drawing effect or flow under greatly reduced pressure over the valve seat and flange 11 and by the lower edge of the valve flange 29. This flow will be sufficient to carry any foreign particles from the valve 10 seat and deposit them either in the pocket 34 or on top of the flange 11 where they can do no injury, when the valve is finally seated. Now, when the valve is again 15 opened, the suction effect above spoken of will lift the particles from the pocket 34 and carry them through the valve and outlet passageway. The valve is centered and guided in the valve chamber by the guide rods 36.

20 My invention, of course, can be readily applied to other forms of valves from that herein shown without departing from the spirit or scope of the invention, the main feature being the relative dimensions of the 25 various flanges and openings whereby wire drawing is primarily in the greater part prevented but just sufficient wire drawing effect retained to cause the valve seat and surface to be automatically cleaned before 30 the valve is closed. A valve of this construction is of particular utility where it is used as a blow-off valve, the blow-off steam usually carrying a great quantity of grit and injurious foreign substances which would 35 soon destroy the valve seat and other surfaces. As the flange 29, however, in my valve is comparatively long and does not finally open a passageway through the valve until the outer flange of the valve has left 40 the seat, there can be no concentration of pressure or flow over the valve seat and consequently no injurious wire drawing effect. The wire drawing effect, however, which is retained is of such low pressure as to be just 45 sufficient to carry the foreign material off the valve seat.

I desire to secure the following claims by Letters Patent:

1. In a valve structure, the combination 50 of an annular valve seat member, a horizontal outer flange extending from said member and having a raised surface forming the valve seat, a vertical flange extending from said valve seat member above the level of the 55 valve seat, a valve having an inner annular flange for engaging with a steam tight fit in the bore of the valve seat member, an outer flange for the valve for engaging the valve seat, and a groove between the outer and inner 60 valve flanges for receiving the vertical flange of the valve seat member, the inner flange of the valve extending lower than the outer flange and also extending below the 65 plane of the valve seat when the valve is closed.

2. In a valve structure, the combination of the inclosing casing having an inlet passageway and an outlet passageway, an annular valve seat member between the passageways having an annular flange providing a valve 70 seat in a plane below the plane of the upper having an annular flange providing a valve- 75 ing an outer flange for engaging the valve seat and an inner flange for engaging with steam tight fit in the valve seat member, said inner flange extending below the outer flange.

3. In a valve structure, the combination of the inclosing casing having an inlet passageway and an outlet passageway, an annular 80 valve seat member between the passageways, an annular flange extending from the valve seat member and providing a valve seat in a plane below the plane of the upper face of the valve seat member, a valve having an 85 outer flange for engaging the valve seat and an inner flange for engaging with steam tight fit in the valve seat member, said inner flange extending below the outer flange, the 90 upper face of the valve seat member being in a plane with the lower edge of the inlet passageway.

4. In a valve structure having an entrance opening, the combination of an annular valve seat member, a horizontal flange extending from the member and forming an annular valve seat below the level of the entrance opening, a flange extending upwardly from the seat member beyond the level of the valve seat, a valve having an outer flange 95 for engaging the valve seat, and an inner flange for the valve longer than the outer flange for engaging with steam tight fit in the bore of the seat member, the length of said inner flange being such that when the 100 valve is raised the outer flange will be above the level of the vertical flange of the seat member before the inner flange leaves the seat member.

5. In a valve structure, the combination of 110 an inclosing casing having an inlet passageway and an outlet passageway at right angles with the inlet passageway, an annular valve seat member disposed in the outlet passageway, a valve seat member providing an 115 annular valve seat lying in a plane below the level of the inlet passageway, a protecting flange extending upwardly from the seat member and within the seat with its upper 120 face in the same plane as the lower edge of the inlet passageway, a valve having an outer flange for engaging the valve seat, and an inner flange for engaging with steam tight fit in the annular seat member, said inner 125 valve flange being of such length that the outer flange will move beyond the level of the seat member protecting flange before the inner valve flange leaves the seat member.

6. In a valve structure, the combination of 130 an inclosing casing having an inlet passage-

way and an outlet passageway at right angles with the inlet passageway, an annular valve seat member disposed in the outlet passageway, a valve seat member providing an annular valve seat lying in a plane below the level of the inlet passageway, a protecting flange extending upwardly from the seat member and within the seat with its upper face in the same plane as the lower edge of the inlet passageway, a valve having an outer flange for engaging the valve seat and an inner flange for engaging with steam-tight fit in the annular seat member, said inner

valve flange being of such length that the outer flange will move beyond the level of the seat member protecting flange before the inner valve flange leaves the seat member, and a pocket formed between the valve seat and protecting flange.

In witness whereof, I hereunto subscribe my name this 15th day of June A. D., 1907.

Correction in Letters Patent No. 905,219.

It is hereby certified that in Letters Patent No. 905,219, granted December 1, 1908, upon the application of Olaf E. Oleson, of Chicago, Illinois, for an improvement in "Valves," an error appears in the printed specification requiring correction as follows: Page 2, claim 2, strike out line 72 and insert the words and syllable *face of the valve seat member, a valve hav-*; and that the said Letters Patent should be read with this correction therein that the same may conform to the record of the case in the Patent Office.

Signed and sealed this 26th day of April, A. D., 1921.

way and an outlet passageway at right angles with the inlet passageway, an annular valve seat member disposed in the outlet passageway, a valve seat member providing an annular valve seat lying in a plane below the level of the inlet passageway, a protecting flange extending upwardly from the seat member and within the seat with its upper face in the same plane as the lower edge of the inlet passageway, a valve having an outer flange for engaging the valve seat and an inner flange for engaging with steam-tight fit in the annular seat member, said inner

valve flange being of such length that the outer flange will move beyond the level of the seat member protecting flange before the inner valve flange leaves the seat member, and a pocket formed between the valve seat and protecting flange.

In witness whereof, I hereunto subscribe my name this 15th day of June A. D., 1907.
